US00D866511S

(12) **United States Design Patent** (10) **Patent No.:** **US D866,511 S**
Lindof (45) **Date of Patent:** **** Nov. 12, 2019**

(54) **HEADSET**(71) Applicant: **RTX A/S**, Nørresundby (DK)(72) Inventor: **Jens Christian Lindof**, Nørresundby (DK)(73) Assignee: **RTX A/S**, Nørresundby (DK)(***) Term: **15 Years**(21) Appl. No.: **29/627,270**(22) Filed: **Nov. 24, 2017**(30) **Foreign Application Priority Data**

May 24, 2017 (EM) 004015972

(51) **LOC (12) Cl.** ..... **14-01**(52) **U.S. Cl.**USPC ..... **D14/206**; D14/226(58) **Field of Classification Search**

USPC D14/206, 205, 225, 226; D29/112, 122; 181/144, 145, 150, 199; 379/430, 431; 381/380, 381, 374, 74; 455/90.3, 475.1, 455/569.1

Primary Examiner — Paula Allen Greene(74) *Attorney, Agent, or Firm* — Merchant & Gould P.C.(57) **CLAIM**

The ornamental design for a headset, as shown and described.

DESCRIPTIONFIG. 1 is a perspective view of a headset showing my new design;
FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a rear perspective view thereof.

The broken lines depict environment that forms no part of the claimed design.

1 Claim, 7 Drawing SheetsUS D866,511 S
